UNITED STATES PATENT OFFICE.

SAMUEL M. KING, OF LANCASTER, PENNSYLVANIA.

IMPROVED BRIDLE-BIT.

Specification forming part of Letters Patent No. 56,762, dated July 31, 1866.

To all whom it may concern:

Be it known that I, SAMUEL M. KING, of the city of Lancaster, county of Lancaster, and State of Pennsylvania, have invented new and useful Improvements in Bridle-Bits; and I do hereby declare the following to be an exact description thereof, reference being had to the accompanying drawings, and to the letters of reference marked thereon, making a part of this specification.

Figure 1 is a view of the bit. Fig. 2 shows how the headstall and reins are to be attached.

The nature of my invention consists in an extension of the mouth-piece of a snaffle-bit, on the outer ends having an aperture and grooved roller for a round rein to work in, for the purpose of drawing the bit upward against the top of the mouth of the horse, and prevent his holding the bit between his teeth, at the same time easy on the horse's mouth, yet enabling the rider to manage and control him with the greatest of ease.

A represents the mouth-piece of a snaffle-bit; B, the rings to which the headstall and the riding-reins are attached. D are the extended ends, having a slot with a grooved roller, E, and an aperture, J, through which a round rein operates, the one end of the round rein being attached to the cheek part of the headstall, then passed through the aperture J, and the other end held in the rider's hand, or to rest on the horse's neck, to be used only when necessary to check the horse, the rein operating against the roller E.

What I claim as my invention, and desire to secure by Letters Patent, is—

The extended ends D, constructed with grooved rollers E and round aperture J, as herein described, and for the purposes set forth.

SAML. M. KING.
